UNITED STATES PATENT OFFICE.

ARTHUR P. THISSELL AND GEORGE S. BRADSTREET, OF BEVERLY,
MASSACHUSETTS.

WASH-BOILER.

SPECIFICATION forming part of Letters Patent No. 408,766, dated August 13, 1889.

Application filed April 1, 1889. Serial No. 305,563. (No model.)

To all whom it may concern:

Be it known that we, ARTHUR P. THISSELL and GEORGE S. BRADSTREET, both of Beverly, in the county of Essex, State of Massachusetts, have invented a certain new and useful Improvement in Wash-Boilers, of which the following is a description sufficiently full, clear, and exact to enable any person skilled in the art or science to which said invention appertains to make and use the same, reference being had to the accompanying drawings, forming part of this specification, in which—

Figure 1 is an end elevation of our improved boiler with the cover in position; Fig. 2, a like view showing the cover in use as a drainer; Fig. 3, a top plan view of the same, the body of the boiler being broken off; and Fig. 4, a vertical transverse section of the drainer.

Like letters and figures of reference indicate corresponding parts in the different figures of the drawings.

Our invention relates to that class of boilers which are employed in washing clothing; and it consists in certain novel features, as hereinafter fully set forth and claimed, the object being to produce a simple, cheap, and effective device of this character.

The nature and operation of the improvement will be readily understood by all conversant with such matters from the following explanation.

In the drawings, A represents the body of the boiler, which is of the ordinary form and construction, and is provided at each end with a handle b.

The cover B is of the usual oval form, and has its sides d extended or broadened. One of the long sides d is cut away or grooved at h. The top f of the cover is flattened at g, said flattened portion being provided with drain holes or perforations i. A disk C is swiveled on the inner face of said flattened portion by means of a key m, said disk being provided with perforations p, adapted to register with the perforations in the cover. The key m is designed to be of such length that it will hold the disk C sufficiently close to the cover to prevent vertical movement thereof, a washer or similar means being employed to

effect this, if necessary. A slotted drain-tray D is disposed within the cover, one edge of said tray being inserted beneath an inwardly-projecting flange r on one side d and secured by a hinged catch t on the opposite side d, the purpose of said tray being to prevent the clothes from obstructing the perforations p. A hook v is hinged to the supporting-flange z of the cover opposite the groove h.

In the use of our improvement the cover B is employed in the usual manner to close the boiler, as shown in Fig. 2, while boiling the clothes, the disk C being turned by the key m so that its perforations will not register with the perforations i in said cover, thus preventing the steam from escaping. After the clothes have been sufficiently boiled the cover is removed, the key m serving as a handle. The cover is then inverted and placed in the boiler at right angles thereto and at one end thereof, as shown in Figs. 3 and 4, it being secured by inserting the hook v in the boiler-handle b. The disk C is revolved by means of the key m so that its perforations p register with the holes i in the flattened portion of the cover. The clothes are taken from the boiler and deposited on the tray D, and the water therefrom will drain through the cover back into the boiler. The groove h is formed in the side d, to enable the clothes to be more readily transferred to the cover.

By detaching the hook v the clothes may be transported in the cover to the rinsing-tubs.

Having thus explained our invention, what we claim is—

1. In a wash-boiler, a cover having a portion of its top flattened and perforated, a disk swiveled to said flattened portion and provided with drain-openings, and a slotted tray adapted to be detachably secured in said cover, all being combined to operate substantially as described.

2. In a wash-boiler, a cover having the central portion of its top flattened and provided with drain-holes, a perforated disk swiveled to said flattened portion, a key for said disk, a slotted tray disposed within said cover, and a flange and catch in said cover for securing said tray, substantially as described.

3. In a wash-boiler, the combination of a body provided with handles, a cover having

elongated sides and a central flattened portion in its top provided with drain-openings, a perforated disk swiveled to said top, a key for revolving said disk, a slotted tray adapted to be inserted in said cover, a flange and catch for detachably securing it therein, and a hook on the supporting-flange of said cover for securing it in an inverted position on said body, all being arranged to operate substantially as described.

4. In a wash-boiler, the combination of the body A, having the handles b, with the cover B, provided with the groove h, perforated flattened portion g, the perforated disk C, key

m, and hook v, arranged to operate substantially as described.

5. In a wash-boiler, the combination of the body A, provided with handles b, the cover B, having the groove h, flattened portion g, and drain-holes i, the perforated disk C, the key m, the tray D, the flange r, and catch t, and the hook v, all being arranged to operate substantially as described.

ARTHUR P. THISSELL.
GEORGE S. BRADSTREET.
